United States Patent Office.

FRANCIS SCHERB, OF SAN FRANCISCO, CALIFORNIA.

Letters Patent No. 95,385, dated September 28, 1869.

IMPROVED SPRING-WAGON.

The Schedule referred to in these Letters Patent and making part of the same.

To all whom it may concern:

Be it known that I, FRANCIS SCHERB, of the city and county of San Francisco, State of California, have invented an Improved Carriage or Spring-Wagon; and I do hereby declare the following description and accompanying drawings are sufficient to enable any person skilled in the art or science to which it most nearly appertains, to make and use my said invention or improvements without further invention or experiment.

The nature of my invention is the construction of an improved carriage or spring-wagon, in which a thoroughbrace is used, in combination with a curved wooden jack, to form the spring; and

It consists in arranging the wooden jacks or springs in such a manner as to be out of the way of the wheels when attempting to turn the wagon; secondly, in an improved clip, for securing the jacks to the head-block and axle-bed.

It also consists in an improved device for securing the ends of the thoroughbraces, so that they can be taken up when they become loose or slack.

The object to be gained is convenience and utility. It also gives a carriage or wagon a better finish of the more noticeable parts, while it gives strength to those parts liable to be the weakest.

In order to give a more full description of my manner of constructing carriages and wagons, reference is had to the accompanying drawings, and the letters marked thereon, forming a part of this specification, of which—

Figure 1 is a perspective view.

Figure 2 is a view of the jack.

Figures 3 to 9, inclusive, are details.

Similar letters of reference, in each of the figures, indicate like parts.

A is the head-block, and B the rear axle-bed of a wagon, and are joined together by the reaches C C.

These reaches approach each other as they near the head-block, and diverge toward the axle-bed B, thus giving more room for the wheel in turning, by allowing it to pass further under the wagon.

The jacks D are made of wood, bent to the proper shape, and bound around the outside with a thin plate of brass.

E are cross-bars, which extend across the reaches at a short distance from the head-block and rear axle-bed, upon which the ends of the bent jacks are placed, resting also upon the head-block and rear axle-bed, where they are secured by clips F.

These clips are made in pairs, and solid, on a metal

plate, a, which, on one side, extends a distance from the clip, as shown in figs. 8 and 9, and is provided with a hole, through which a bolt, i, (shown in figs. 5 and 7,) passes.

This clip is used to secure the bent jacks D to the head-block, the plates e resting on the top of the jack, and the clips passing down on each side of the axle-bed and head-block, where it is secured, as above described, by the bolt i, thus rendering it perfectly solid.

The leather thoroughbraces G G are fastened through the head-block A and through the axle-bed B, by means of a split iron strap-bolt, H, shown in figs. 6 and 7, and are screwed into the metal shoulders I, and secured with nuts, by means of which the thoroughbraces can be taken up or shortened when they become slack.

At the upper ends of the jacks are staples K, shown at figs. 3 and 4. The thoroughbraces pass through these staples, and are thus prevented from slipping from the jacks.

The staples are confined to the jacks by means of metal straps c, which pass around under the jacks, and thus hold them firm; and may be either continuous from one side to the other, as shown at fig. 4, or may simply be two arms, bent under and meeting in the centre, as in fig. 3.

By thus constructing a carriage or wagon, much greater strength is obtained, and the bent jacks are not liable to settle, being arranged independent of the reaches, while, by the use of the solid clips, they are secured to the head-block and rear axle-bed so firmly that they cannot give from their proper position; and the mode of securing the thoroughbraces is such that their tension can be easily changed.

Having thus described my invention,

What I claim, and desire to secure by Letters Patent, is—

1. The reaches C C, in combination with the cross-bars E E and bent wooden jacks D, the whole arranged substantially as herein described.

2. The combination of the split strap-bolt H and shoulder I, for securing the ends and regulating the tension of the thoroughbraces, substantially as described.

In witness whereof, I have hereunto set my hand and seal.

FRANCIS SCHERB. [L. S.]
